Patented Feb. 21, 1911.

UNITED STATES PATENT OFFICE.

GUY HOLSOOPPLE, OF HOLSOOPPLE, PENNSYLVANIA.

RAILWAY MAIL-EXCHANGER.

984,814.

Specification of Letters Patent.

Patented Feb. 21, 1911.

Application filed August 22, 1910. Serial No. 578,415.

To all whom it may concern:

Be it known that I, GUY HOLSOOPPLE, a citizen of Hollsopple, in the county of Somerset and State of Pennsylvania, have 5 invented a new and useful Improvement in Railway Mail-Exchangers, of which the following is a specification.

This invention relates to an improved railway mail exchanging apparatus, and its object is to provide a satisfactory device for the convenient and mutual exchange of light or heavy mail and the like with moving trains with minimum damage to the articles exchanged, and is characterized by extreme 15 efficiency and simplicity in construction.

The predominating feature of the apparatus is: that, instead of making the exchange of mail-bags by having them come in direct contact with their respective rigid 20 catching-devices, as is the case in devices now commonly used, the mail-bags are secured to the lower end of a long suspended cable and the exchange is made by catching the upper end of the cable on the outer end 25 of a swinging arm as the car passes. In so doing the mail bags are left free to describe an easy swinging motion, which greatly reduces the impact, a result especially desired 30 in the exchange of heavy mail with swift-moving trains.

A preferable embodiment of the invention is shown herein and will be understood by the accompanying drawings and the following description and claims.

35 In the drawing, Figure 1 is a perspective view of a section of a railway mail car, with the parts in operative position for the mutual discharge and receipt of mail-bags. Fig. 2 is an enlarged side view of the upper 40 end of the cable with the node in section. Fig. 3 is an enlarged perspective view of the spring washer; and Fig. 4 is a plan view of the outer end of the arms 2 as seen in Fig. 1.

The numeral 1, Fig. 1, represents the body 45 of a mail car having the combined delivering and receiving device or arm 2 perpendicularly hinged to the eyes 3 and 3', which are secured to the outer wall of the car near the upper forward corner of its side door 50 and in a manner permitting said device or arm to extend outwardly from the car and to swing substantially in a horizontal plane under impact. A spring washer 4 is placed between the upper eye 3 and the nut 5, which

is threaded on the angular inner end of the 55 device or arm 2 so as to frictionally resist a too easy swinging of the device or arm. A hook 7 projects outwardly from the outer end of the arm on which the eye 8 formed on the spherical stop or node 9 is adapted to 60 releasably hang, thus suspending therefrom the cable 10 to which the stop or node is secured. The cable has formed at its lower end a loop 12 to which the mail bags 14 are attached by the band 13, and are releasably 65 suspended by the loop from the hook 11, located on the outer wall of the car near the lower forward corner of its side door.

A track standard 15 is located beside the track and has hinged to it the receiving device or arm 16 by the eyes 3 and 3' in a manner permitting it to extend trackward and to swing substantially in a horizontal plane under impact. A spring washer 4' is also attached to it by the bur 5' similar to 75 and for the same purpose as that of the spring washer 4, above indicated.

The arm 16 is adapted to lie in a plane slightly below that of the arm 2 with its outer end underlapping the outer end of the 80 arm 2 when in operative positions. The arm 16 has its outer end curved about rearwardly forming a jaw or bight 17, and when the arm 2 passes over the arm 16, the upper part of the cable, at a point slightly below 85 the stop or node, strikes the rearward edge of the arm 16 at a point slightly inward from the opening of its jaw or bight, then in the forward movement it pushes the arm 16 forwardly. The cable slides outwardly 90 along the edge of the arm and enters the jaw or bight. The cable is pulled from the device or arm 2 and is drawn downwardly through the jaw or bight until it reaches the stop or node, which is too large to slip 95 through the jaw or bight. Thus the mail-bags are pulled from the hook 11 and are permitted to swing gracefully around to the rear of the standard 15 to be removed by the local operator. Instead of the jaw or 100 bight's being constructed with the usual V-shaped mouth with the two branches of the V about equal in length, the outward branch is considerably shortened, being only of sufficient length to form the base, or the jaw or 105 bight proper, and it is curved about spirally as indicated in the drawing, Fig. 2, to prevent the accidental displacement of the cable

after it has once entered into the jaw or bight proper, thus avoiding the use of a detent spring for the purpose. The bag holding jaws are in the form of flat spirals, so that the terminals of the jaws will act as guards to prevent the accidental removal of the bags, under the influence of the momentum imparted thereto by the rapidly moving trains, and these terminals are directed 10 inwardly so that the linear thrust of the bags will be converted into a rotary motion, thereby dissipating the force of the thrust. The trackward, or inner branch of the V is, of course, long, consisting of the device or 15 arm itself which the cable strikes before entering the jaw or bight proper. Then, instead of the cable's deviating from its path to follow along on the arm, to the jaw or bight proper, the device or arm itself is pushed 20 forwardly on its hinge by the cable, and the jaw or bight proper swings into line with the cable and the results are as above indicated.

A track standard 18 is also located beside 25 the track distantly forward from the standard 15 and carries a delivery device or arm 19 adapted to extend trackwardly therefrom in a plane slightly above that of the arm 2 and with its outer end overlapping the outer 30 end of the arm 2 when in operative position. The arm 19 has a trackwardly extending hook 20 located on its outer end from which another cable 10, having attachments similar to those of the cable 10 above described, 35 is adapted to releasably suspend, while the mail-bags 14 which are attached to the cable are suspended by the loop 12 from the hook 21 of the track standard.

In order that the device or arm 2 may be 40 used as a cable-catching arm as well as a cable-holding arm, its outer end is curved about forwardly forming a jaw or bight 6 similar to that of the jaw or bight 17 above described. The train operator, upon approaching the place of exchange, holds the device or arm 2 rigidly outward from the car until it has passed the arm 16 and has been relieved of its cable and the attached mail-bags; and when the device or arm 2 45 reaches the arm 19, the operator yieldingly allows the device or arm 2 to move rearwardly under the pressure of the cable 10 of the track standard 18. The cable enters the jaw or bight 6 by an operation similar to 50 that of the arm 16 above described, the mail bags are similarly pulled from the hook 21 of the track standard and are permitted to swing rearwardly across the side door of the car to be pulled into the car and removed 55 by the train operator.

The device may be readily adapted to operate in either direction on the same side of the track. To do so, a track-standard, similar in equipment to that of the standard 18 60 above described, is placed on either side of

the standard 15. The devices or arms 2 and 16 are each furnished with two jaws or bights, one opening on either side of each device or arm, and a pair of eyes 3 and 3, and a hook 11 are placed in corresponding 70 positions respectively on either side of the side door of the car so that the device or arm 2 may be readily transferred from one set of eyes to the other by removing the nut 5 with the spring washer 4 and using them in the 75 readjustment of the device or arm.

In order that the cables may be used interchangeably, they and their respective attachments are constructed of uniform dimensions and the distances between the 80 outer end of each cable-holding arm and the respective bag-holding hooks are uniform.

What I claim and desire to secure by Letters Patent is:

1. A mail bag handling device comprising 85 a mail bag receiving arm having flat spiral bag holding means thereon.

2. A mail bag handling device comprising 90 means having a flat spiral bag holding jaw thereon.

3. A mail bag handling device comprising 95 means for supporting a mail bag having a horizontally disposed flat spiral bag holding jaw.

4. A mail bag handling device comprising 100 supporting means having a horizontally disposed flat spiral bag holder.

5. A mail bag handling device comprising 105 a horizontally swinging bag holder having a flat spiral jaw and adapted to be carried by a car and a flexible cable having a stop on one end adapted to engage the flat spiral jaw of the bag holder and having bag securing means on the other end.

6. A mail bag handling device comprising 110 a flexible cable adapted to be secured at one end to a mail bag and provided with a stop, and bag receiving means having a flat spiral jaw for attachment to a car for engaging the flexible cable and the stop and 115 adapted to permit a bag secured to said flexible cable to swing toward the car.

7. A mail catcher comprising an arm with 120 one of its ends frictionally hinged to a support in a manner permitting it to swing in a horizontal plane under impact and adapted to extend outwardly therefrom substantially in a horizontal plane and at right angles to the railroad track, having formed at its outer end a bight with the mouth thereof opening in the direction of the approaching mail bags to be caught and in a manner adapted to engage therein a cable to which the mail-bags are attached, that is held uprightly in its path; said arm having also 125 means for swinging and holding same into or out of its operative position, all substantially as alleged.

8. A mail bag handling device comprising 130 a horizontally swinging arm having a flat

- spiral jaw and a flexible cable having a spherical stop at one end to engage the jaw and adapted to be secured at the other end to a mail bag.
- 5 9. In a mail bag handling device, a swinging arm having a spiral and horizontally disposed flat spiral terminal jaw, a flexible cable adapted to be secured to a mail bag having a stop to engage the jaw, and means 10 for supporting the cable in position to be engaged by the terminal jaw of the arm.
- 10 10. In a mail bag handling device, a swinging arm having a flat spiral horizontally disposed jaw, means for supporting the 15 arm on a car for horizontally swinging movement, and a bag supporting member adapted to be engaged by the spiral jaw.
- 15 11. In a mail bag handling device, a swinging arm mounted for horizontal movement and formed with a flat spiral jaw having its mouth disposed laterally of the arm, and bag supporting means having a stop thereon and adapted to engage the jaw.
- 20 12. In a mail handling device, a swinging 25 arm having bag holding means thereon, said arm being formed with an angular end, an eye for supporting said arm for swinging movement, a nut threaded on the angular end, and a spring washer interposed between 30 the eye and the nut on said angular end.
- 25 13. In a mail bag exchanger, a car carried 35 device comprising a bag supporting member having a hook thereon for supporting a bag to be delivered and a spiral jaw for receiving a bag, and means for supporting the member for swinging movement; and a stationary device comprising a support, an arm 40 swingingly mounted on the support and formed with a spiral jaw; and a bag support comprising a flexible cable adapted to 45 be secured at one end to a mail bag and having a stop on the other end and an eye extending from the stop, the stop being adapted to engage the jaws of the car carried member and the stationary arm.
- 30 14. In a mail bag exchanger, a car carried mail bag delivering and receiving device comprising, eyes, an arm mounted on the eyes for swinging movement, means for 50 securing the arm to the eyes, a support adapted to be secured on a car below the arm, said arm being provided with a spiral jaw extending from the end thereof and a hook extending from said jaw, and a cable 55 of flexible material having a stop on one end to engage the spiral jaw and an eye to engage the hook extending from said jaw and means on the other end to engage support and to be secured to a mail bag.
- 55 15. In a mail bag exchanger, a car carried device comprising a swinging arm having a terminal spiral jaw and a hook, a bag holder consisting of a flexible cable having a stop on one end and an eye adjacent the stop and a loop on the other end, said loop 60 being adapted to be secured to a mail bag, and a support located below the arm adapted to engage the loop and hold the bag carried by said cable against swinging; a stationary support, a swinging arm carried by 65 the support and provided with a spiral terminal jaw adapted to engage the cable and the stop thereof; and a second stationary support located distantly from the first stationary support and having an arm provided with a terminal hook adapted to hold a bag supporting cable so that the stop of said cable will be engaged by the terminal jaw of the car carried arm.
- 70 16. A mail bag exchanger comprising, a 75 stationary support, an arm having a spiral terminal jaw, means for securing the arm to the support for swinging movement, a friction member mounted on said arm for preventing the free movement thereof under impact; a bag supporting member consisting of a flexible cable having means on one end to be secured to a mail bag and a stop and eye on the other end, said stop being adapted to engage the spiral terminal jaw; a second 80 stationary support located distantly from the first stationary support and provided with an arm having a terminal hook adapted to engage the eye of said cable and releasably support said cable thereby, a support 85 on said second stationary support adapted to hold a mail bag carried by said cable against swinging; and a car carried device comprising a swinging arm having a spiral terminal jaw and a hook adjacent 90 said jaw, a support located below the arm, and a second flexible cable having a stop on its upper end to engage the terminal jaw of said last arm and an eye to engage the hook 95 thereof, the hook of said last arm being adapted to hold the second cable in position to be delivered to the first arm, said cable being adapted to be secured to a mail bag at its lower end and having means to 100 engage the support of the car carried device, whereby the mail bag carried by said second cable will be held against swinging.
- 105 17. In a mail bag exchanger, a mail bag supporting arm having a horizontally disposed flat spiral terminal jaw adapted to hold a mail bag, the terminal of said jaw being directed inwardly to act as a guard therefor and prevent the accidental removal of a mail bag supported by the jaw.
- 110 18. A mail bag exchanger comprising a 120 cable arranged at one of its ends for attachment to a mail bag and having a node secured at the other end, a delivery arm for releasably supporting the node, and a support for the mail bag located remotely below the 125 arm; in combination with a catcher comprising an arm with one of its ends frictionally hinged to a support in a manner permitting it to swing in a horizontal plane under impact and adapted to extend outwardly there-

from substantially in a horizontal plane and at right angles to the line of travel, said arm having formed on its outer end a spiral jaw with the mouth thereof opening on the side 5 of the arm toward the direction of delivery and in a manner adapted to engage the cable.

In testimony whereof, I have signed my name to these specifications in the presence of two subscribing witnesses.

GUY HOLSOOPPLE.
